ELECTRIC MOTOR DRIVE FOR WEB PRINTING, CUTTING AND FOLDING MECHANISM

Application filed July 3, 1929. Serial No. 375,829.

My invention relates broadly to an electric motor drive for web printing, cutting and folding mechanisms, which drive includes master and auxiliary motors and control means for maintaining the auxiliary motors at predetermined speeds relative to the master motor.

My invention comprises a plural electric motor drive for the mechanism for printing on a running web, for the mechanism for cutting sheets from the printed web, for the mechanism for collecting and folding the so-cut sheets and for the mechanism for feeding the printed web to the cutting mechanism; novel control means being provided whereby the variations in the speed of the auxiliary motors will be automatically corrected to maintain the auxiliary motors at predetermined relative speeds with respect to the speed of the master motor.

My invention also comprises web tension controlled means for varying the speed of the auxiliary motor which drives the mechanism for feeding the printed web to the cutting mechanism and also where a plurality of printing units are provided for varying the speed of the auxiliary motor for one of the printing units, to bring the printing units into proper register with respect to the web.

My invention is shown in connection with a two printing unit perfecting rotary web printing press where two colors are printed on each side of the web.

A practical embodiment of my invention is represented in the accompanying drawings, in which

Fig. 1 represents a diagrammatic plan view showing the electric equipment for the several mechanisms with my novel control means associated therewith;

Fig. 2 represents a diagrammatic side view of such mechanisms; and

Fig. 3 represents on an enlarged scale one of the control mechanisms represented in Fig. 2.

It will be understood that the several parts of the electric equipment shown may be of any well known or approved construction.

The web 1 is first led around the impression cylinder 2 of the first printing unit to be

printed on one side by the form cylinders 3 and 4 and then around the impression cylinder 5 of the second printing unit to be printed on the other side by the form cylinders 6 and 7.

An offset web 8 is fed from its supply roll 9 around the impression cylinder 5 and from thence to its rewinding roll 10 which may be driven by a suitable electric motor 11. The printed web is then fed around the rolls 12 of the mechanism for feeding the web in register to the coacting rotary cutters 13, 13 of the cutting mechanism for severing the web transversely into sheets. From there the sheets are fed to the folding cylinders 14, 14 of a sheet collecting and folding mechanism from whence they are passed to a suitable delivery mechanism 15.

It will be understood that the feeding, cutting and folding mechanisms may all be of any well known or approved construction and arrangement.

The first printing unit is shown as driven by a master motor 16, the second printing unit by an auxiliary motor 17, the web feeding mechanism by an auxiliary motor 18, the cutting mechanism by an auxiliary motor 19 and the folding mechanism by an auxiliary motor 20. These motors derive their power from a motor-generator 21 through its manually operated voltage control 22 which controls the speed of the master motor 16 and the normal relative speeds of the auxiliary motors 17, 18, 19 and 20 by voltage control of the generator. The master motor 16 is shown as driving a longitudinal shaft 23 through bevel gearing 24, which shaft drives a pulley 25 through bevel gearing 26. The shaft of the auxiliary motor 17 is shown as provided with a cone pulley 27 which drives a reverse cone pulley 28 on a cross shaft 29 through a belt 30. A pulley 31 is mounted on this shaft 29. Pulleys 32, 33 are carried by rock levers 34, 35, the free ends of which are connected by a flexible connection, in the present instance a sprocket chain 36 with a sprocket 37 on the shaft of the contact arm 38 of a control rheostat 39. A belt 40 passes around the pulleys 25, 31, 32, 33. Springs 41, 42 serve the double purpose of holding

the levers 34, 35 of the rheostat arm 38 in their neutral positions and also of holding the driving belt 42 under slight tension.

The master motor shaft 23 has a bevel gear driving connection 43 with a vertical shaft 44 which, in turn, has a bevel driving gear connection 45 with a horizontal shaft 46 which carries a pulley 47. The shaft of the auxiliary motor 20 has a cone pulley 48 which drives through a belt 49 a cone pulley 50, the shaft 51 of which carries a belt pulley 51. Pulleys 52, 53 are carried by the rock levers 54, 55, the free ends of which are connected by a flexible connection, in the present instance a sprocket chain 56 with a sprocket 57 which carries the contact arm, not shown, of the controlled rheostat 58. Springs 59, 60 serve the double purpose of holding the levers 54, 55 and the rheostat arm in their neutral positions and also of holding the driving belt 61 under slight tension, which passes around the pulleys 47, 51, 52, 53.

The vertical shaft 44 has a bevel gear driving connection 62 with a cross shaft which carries a pulley 63. The shaft of the auxiliary motor 19 has a cone pulley 64 which drives through a belt 65, a reverse cone pulley 66 which also carries a belt pulley 67 above the pulley 63.

Pulleys 68, 69 are carried by the rock levers 70, 71, the free ends of which are connected by a flexible connection, in the present instance a sprocket chain 72 with the sprocket 73 on the axis of the contact arm 74 of a control rheostat 75. Springs 76, 77 serve the double purpose of holding the levers 70, 71 and rheostat arm 74 in their neutral positions and also of holding the driving belt 78 which passes around the pulleys 63, 67, 68, 69, under slight tension.

The vertical shaft 44 drives a short longitudinal shaft 79 through a bevel gear driving connection 80, which shaft 79 drives a short vertical shaft 81 through a bevel gear driving connection 82. This vertical shaft 81 drives a horizontal shaft 83 through a bevel gear driving connection 84. This shaft 83 has a pulley 85 thereon. The shaft of the auxiliary motor 18 has a cone 86 which is connected to a reverse cone 87 on the shaft 88 by a belt 89. Pulleys 90, 91 are carried by the rock levers 92, 93, the free ends of which are connected by a flexible connection, in the present instance a sprocket chain 94 with a sprocket 95 carried by the shaft of the contact arm 96 of the control rheostat 97. Springs 98, 99 serve the double purpose of holding the levers 92, 93 and the rheostat arm 96 in their neutral positions and also of holding the driving belt 100 which passes around the pulleys 85, 88, 90, 91, under slight tension.

The means for varying the tension of the web as it passes from one printing unit to the other printing unit to bring the printing units into register on the web is as follows:

The web 1 as it leaves the first printing unit passes over a roller 101 held under upward stress by a weighted flexible connection 102 tending to take up the slack in the web between the two printing units. This roller 101 is connected by a rod 103 with a bell crank lever 104 which, in turn, is connected by a rod 105 with a belt shifter fork 106 which embraces the belt 30. The web 1 also passes over a roller 107 carried by a two armed lever 108, 109 provided with a hand micrometer adjustment 110 of any well known or approved form.

The printed web 1 as it passes to the feeding mechanism is led around a roller 111 held under upward stress by a weighted flexible connection 112 tending to take up the slack in the web. This roller 111 is connected by a rod 113 with a bell crank lever 114 which, in turn, is connected by a rod 115 with a belt shifter fork 116 which embraces the belt 89. The web on its way to the feeding mechanism also passes between rollers 117, 118 carried by a two armed lever 119, 120 provided with a hand micrometer adjustment 121 of any well known or approved form. The control mechanisms per se hereinabove described form the subject matter of my copending application filed of even date herewith, its serial number being 375,827.

When the auxiliary motors 17, 18, 19 and 20 are running at predetermined speeds with respect to the speed of the master motor 16, their rheostat control arms are held in their neutral positions as well as their controlling rock levers. Should any of these auxiliary motors start to run "ahead" or "behind" the additional pull on their control device belts will cause their rock levers to move in opposite directions, thereby causing their rheostat arms to move along their contacts in one or the other direction from their neutral positions, thereby causing their respective auxiliary motors to "slow down" or "speed up" to their predetermined relative speeds with respect to the master motor 16. Should the web run "ahead" or "behind" from the first printing unit to the second printing unit the additional compensating device will come into action to shift the belt 30 on its reverse cone pulleys 27, 28 to vary the speed of the auxiliary motor 17 with respect to the master motor 16. The micrometer adjustment may also be used to bring the first and second printing units into proper register by varying the distance which the web 1 travels from the first printing unit to the second printing unit. In a like manner the web as it enters the feeding mechanism may be controlled by the compensating device and micrometer adjustment device.

From the above description it will be seen that any variation in the speeds of the auxiliary motors will be automatically corrected to bring them into their relative speeds with

respect to the master motor as well as ensuring the proper register between the first and second printing operations and the proper feeding register for the printed web to the cutting mechanism.

5 While I have illustrated my invention in connection with a two printing unit web perfecting printing press with two colors on each side it is evident that I do not wish to limit myself to such a press but contemplate 10 the use of my invention in connection with various types of presses where the equipment is applicable.

What I claim is:—

15 1. Web printing and folding mechanisms and an electric motor drive therefor including a source of electric power, a master motor for the printing mechanism and an auxiliary motor for the folding mechanism, and means for automatically maintaining the auxiliary motor at a predetermined speed relative to the master motor.

20 2. Web printing and folding mechanisms and an electric motor drive therefor including a source of electric power, a master motor for the printing mechanism and an auxiliary motor for the folding mechanism, and means for automatically maintaining the auxiliary motor at a predetermined speed relative to the master motor, said means including an automatically controlled rheostat.

25 3. Web printing, cutting and folding mechanisms and an electric motor drive therefor including a source of electric power, a master motor for the printing mechanism and auxiliary motors for the cutting and folding mechanisms, and automatic means for maintaining the auxiliary motors at predetermined speeds relative to the master motor.

40 4. Web printing, cutting and folding mechanisms and an electric motor drive therefor including a source of electric power, a master motor for the printing mechanism and auxiliary motors for the cutting and folding mechanisms, and automatic means for maintaining the auxiliary motors at predetermined speeds relative to the master motor, said means including automatically controlled rheostats.

45 5. Web printing, cutting and folding mechanisms and an electric motor drive therefor including a source of electric power, a master motor for one printing unit, an auxiliary motor for the other printing unit and auxiliary motors for the cutting and folding mechanisms, and automatic means for maintaining the auxiliary motors at predetermined speeds relative to the master motor.

60 6. Web printing, cutting and folding mechanisms and an electric motor drive therefor including a source of electric power, a master motor for one printing unit, an auxiliary motor for the other printing unit and auxiliary motors for the cutting and folding mechanisms, and automatic means for maintaining

the auxiliary motors at predetermined speeds relative to the master motor, said means including automatically controlled rheostats.

70 7. Web printing, cutting and folding mechanisms and an electric motor drive therefor including a source of electric power, a master motor for one printing unit, an auxiliary motor for the other printing unit and auxiliary motors for the cutting and folding mechanisms, automatic means for maintaining the auxiliary motors at predetermined speeds relative to the master motor, and web tension controlled means for varying the speed of the printing unit auxiliary motor.

75 8. Web printing, cutting and folding mechanisms and an electric motor drive therefor including a source of electric power, a master motor for one printing unit, an auxiliary motor for the other printing unit and auxiliary motors for the cutting and folding mechanisms, automatic means for maintaining the auxiliary motors at predetermined speeds relative to the master motors, said means including automatically controlled rheostats, and web tension controlled means for varying the speed of the printing unit auxiliary motor.

80 In testimony that I claim the foregoing as my invention, I have signed my name this 26th day of June, 1929.
